(57) **CLAIM**

The ornamental design for a golf club head, as shown and
described.

DESCRIPTION

FIG. 1 is a perspective view of a golf club head, as viewed
from the rear and one side thereof.

FIG. 2 is a front elevation view of the golf club head of FIG.
1.

FIG. 3 is a rear elevation view of the golf club head of FIG.
1.

FIG. 4 is a side elevation view of a toe side of the golf club
head of FIG. 1.

FIG. 5 is a side elevation view of a heel side of the golf club
head of FIG. 1.

FIG. 6 is a top plan view of the golf club head of FIG. 1; and,
FIG. 7 is a bottom plan view of the golf club head of FIG.
1.

The broken lines in the drawings are for purposes of
illustrating environmental structure as well as portions of the
design that form no part of the present claimed design.

1 Claim, 4 Drawing Sheets
